(57) **CLAIM**

The ornamental design for a remote controller for air conditioner, as shown and described.

DESCRIPTION

FIG. 1 is a front view of the remote controller for air conditioner showing our new design;

FIG. 2 is a rear view thereof;

FIG. 3 is a right side view thereof;

FIG. 4 is a left side view thereof;

FIG. 5 is a top (plan) view thereof;

FIG. 6 is a bottom side view thereof;

FIG. 7 is a sectional view taken along line 7—7 of FIG. 1 with the internal mechanism omitted;

FIG. 8 is a sectional view taken along line 8—8 of FIG. 1 with the internal mechanism omitted;

FIG. 9 is a front elevation view of FIG. 1, where the lid is opened;

FIG. 10 is a side elevation view of FIG. 3, where the lid is opened; and,

FIG. 11 is a front elevation view of FIG. 1 of an open lid state and an electrified state.
